UNITED STATES PATENT OFFICE

153,397

DESIGN FOR A DRESSING TABLE

Isidor Schwartz, New York, N. Y., assignor to
 I. Schwartz Glass & Mirror Co., New York, N. Y.

Application March 4, 1947, Serial No. 137,324

Term of patent 7 years

(Cl. D33—7)

To all whom it may concern:

Be it known that I, Isidor Schwartz, a citizen of the United States, residing at New York city, in the county of The Bronx and State of New York, have invented a new, original, and ornamental Design for a Dressing Table, of which the following is a specification, reference being had to the accompanying drawing, forming part thereof.

Fig. 1 is a perspective view of a dressing table, showing my new design.

Fig. 2 is a top plan view thereof.

Fig. 3 is a front elevation view of the central portion of the article shown in Fig. 1, and drawn to an enlarged scale.

Fig. 4 is a sectional view taken on line 4—4 of Fig. 3.

I claim:

The ornamental design for a dressing table, substantially as shown.

ISIDOR SCHWARTZ.
